UNITED STATES PATENT OFFICE.

ERNEST FRANKLIN, OF PORTLAND, OREGON.

INTERNAL-COMBUSTION ENGINE.

998,570.

Specification of Letters Patent. Patented July 18, 1911.

Application filed December 28, 1909. Serial No. 535,295.

To all whom it may concern:

Be it known that I, ERNEST FRANKLIN, a citizen of the United States, residing at Portland, in the county of Multnomah and 5 State of Oregon, have invented new and useful Improvements in Internal-Combustion Engines, of which the following is a specification.

This invention provides an engine of the 10 explosion variety and has for its object to supply an internal combustion engine which may be readily started or reversed without requiring the usual cranking or movement of the piston to obtain compression in the cylinder and ignition thereof, since the piston in the present form of engine will at all 15 times stop at an approximately predetermined position which is off a dead center, hence the engine is practically self-starting. 20 A further purpose of the invention is the provision of an engine of the type herein specified, which involves a comparatively simple and compact structure and in which two engines have a tandem arrangement and 25 are related so that one engine supplies the other with the gaseous mixture, the result being that two explosions are obtained in each revolution of the crank shaft.

A further purpose of the invention is the 30 construction of an engine combining a fluid pump, whereby the gaseous mixture is inspirated and aspirated at each stroke of the piston with the result that a co-operating companion engine may be supplied with a 35 proper charge when nearing the end of its combustion stroke and immediately after the exhaust ports have been uncovered to permit the gases resulting from the combustion to quickly escape.

40 The invention consists of the novel features, details of construction and combination of parts, which hereinafter will be more particularly set forth, illustrated in the accompanying drawings, and pointed out in 45 the appended claims.

Referring to the drawings, forming a part of the specification, Figure 1 is a central longitudinal section of an internal combustion engine embodying the invention. Fig. 50 2 is a sectional view similar to Fig. 1 taken on a plane at right angles thereto. Fig. 3 is a horizontal section on the line 3-3 of Fig. 1. Fig. 4 is a horizontal section on the line 4-4 of Fig. 2.

55 Corresponding and like parts are referred to in the following description, and indi-

cated in all the views of the drawings, by the same reference characters.

The engine comprises two cylinders 1 and 2 having a tandem arrangement and separated by a partition 3 forming a head common to each. The outer ends of the cylinders 1 and 2 are open and said cylinders may be cooled in any manner and as shown they are provided with a plurality of external 60 heat dissipating ribs or projections. The partition or head 3 is inclined to the axis of the cylinders, thereby enabling the inlet ports 4 and 5 to occupy a position as near a central line as practical, with the result 65 that the cylinders may be of a minimum length. Collars 6 are in line with the respective inlet openings 4 and 5 and are adapted to have spark plugs or igniting devices of any type fitted thereto. Other cylinders 7 and 8 project outward from the respective cylinders 1 and 2 and are of larger 70 diameter and may form a part thereof or be connected thereto in any manner. A pipe 9 connects the inner end of the cylinder 7 with 75 the inlet 5 of the cylinder 2. A pipe 10 connects the inner end of the cylinder 8 with the inlet 4 of the cylinder 1. A valve 11 closes the end of the pipe 9 adjacent the inlet 5. A valve 12 closes the inner end of the 80 pipe 10 adjacent the inlet 4. Each of the valves 11 and 12 is provided with a stem 13 and is adapted to be closed upon its seat by means of a spring 14. The valve stems 13 are of a length to insure opening of the 85 respective valves at the proper time, whereby the engine cylinders may be charged at the proper moment. Guide sleeves 15 and 16 are provided and have connection at their outer ends with the respective cylinders 7 90 and 8, their inner ends being open and spaced from the respective cylinders 1 and 2. A cap ring 17 connects the outer ends of the guide sleeve 15 and the cylinder 7. The outer or lower ends of the guide sleeve 16 95 and cylinder 8 are connected to a crank case 18, in which the crank portion 19 of a crank shaft 20 operates. A cylindrical space 21 is formed between the guide sleeve 15 and cylinder 7. A cylindrical space 22 is formed 100 between the guide sleeve 16 and the cylinder 8. A pipe 23 connects the outer end of the space 21 with a valve casing 25. A pipe 24 connects the outer end of the space 22 with said valve casing 25. A double piston valve 105 26 is arranged within the valve casing 25 and controls admission of compressed air to

the pipes 23 and 24 when it is required to start the engine. A collar 27 is provided upon the valve casing 25 at a point midway between the points of connection of the pipes 5 23 and 24 with said valve casing. By proper movement of the valve 26 air may be supplied to one or the other of the spaces 21 and 22, as will be readily understood on reference to Fig. 2. A rod 28 connects the 10 valve 26 with an eccentric 29 arranged to cooperate with a cam 30 mounted upon the crank shaft 20 and adapted to be moved so as to vary the relative position of the valve 26 according to the required direction of 15 operation of the engine.

A piston 31 is arranged to operate in the cylinder 1 and is provided with a tubular extension 32, which is adapted to fit close against the inner walls of the cylinder 1 20 and close upon the cylinder 15. The tubular extension 32 has its walls of uniform thickness throughout its length so as to fit close against the walls of the respective cylinders 1 and 15 throughout the length 25 of the stroke of the piston. An annular piston 33 is provided at the outer end of the tubular extension 32 and is arranged to operate in the space 21 and fits close against the walls of the guide sleeve 15 and the 30 cylinder 7. A piston 34 is arranged to operate in the cylinder 2 and has a tubular extension 35, which is provided at its outer end with an annular piston 36 arranged to operate in the cylindrical space 22. The tubular extension 35 is adapted to fit close 35 against the walls of the cylinder 2 and guidesleeve 16, whereas the piston 36 obtains a close fit against the walls of the guide sleeve 16 and the cylinder 8. A pitman 37 40 connects the piston 34 with the crank 19. The two pistons 31 and 34 are connected for simultaneous movement. Rods 38 connect the pistons 31 and 34 and are arranged exterior to the cylinders 1 and 2 and are joined 45 at their ends to the pistons 33 and 36.

The construction is such as to insure a compact arrangement of the parts which is of material advantage in the provision of an engine involving a light construction and 50 adapted to be placed so as to occupy a minimum amount of space. Moreover the engine will not stop upon a dead center, since the pistons in the respective cylinders will occupy a position to admit of one counter-balancing the other. The exhaust ports are 55 located near the outer ends of the respective cylinders and are indicated at 39 for the cylinder 1 and at 40 for the cylinder 2. When the piston 34 moves outward or downward the cylinder 2 receives a charge from the space 21 through the pipe 9 and inlet 5. At the same time the piston 31 is moved 60 inward in the cylinder 1 and compresses the charge therein preliminary to combustion. 65 The piston 36 moving outward in the space

22 creates a suction therein and draws in a charge through a valve controlled inlet 41 provided at the inner end of the cylinder 8. The valve controlled inlet 42 at the inner end of the cylinder 7 remains closed during the out or down stroke of the piston 34, hence the charge previously received in the space 21 is forced therefrom by the piston 33 into the cylinder 2 in the manner stated. When the charge in the cylinder 1 is exploded 70 the piston 31 is driven outward, thereby causing the piston 34 to move inward and compress the charge in the cylinder 2 and at the same time the piston 36 moving inward in the space 22 forces the 75 charge from said space into the cylinder 1. At this time the piston 33 moves outward in the space 21 and draws in a charge through the inlet 42. It should be stated that during the combustion stroke of the pistons the 80 charge contained in either of the spaces 21 or 22 is compressed until the piston has cleared the exhaust openings of its cylinder, thereby providing an escape for the products of combustion, after which the valve 85 controlling the inlet opening is unseated by the piston connected with the compression piston coming in contact with the valve stem. This may be better understood upon considering the piston 34 moving outward 90 on the combustion stroke and the piston 31 moving inward on the compression stroke. When the piston 34 reaches a point in its movement to uncover the exhaust ports 40 so as to provide ample escape for the products 95 of combustion the piston 33 connected with the compression piston 31 comes in contact with the stem of the valve 11 and opens the same, thereby permitting the compressed charge to rush from the inner end of the 100 space 21 into the cylinder 2 and at this instant the charge compressed in the cylinder 1 is ignited and drives the piston 31 outward, thereby causing the piston 34 to move 105 inward and compress the charge contained 110 in the cylinder 2.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the embodiment thereof, 115 I desire to have it understood that the device shown is merely illustrative, and that such changes may be made when desired as are within the scope of the claims appended hereto.

Having thus described the invention what is claimed as new, is:—

1. In combination, two engine cylinders, pistons arranged to work therein and connected for simultaneous movement, other 130

- 5 cylinders, a second set of pistons connected with the first mentioned pistons and arranged to operate in the second set of cylinders, the parts being disposed to admit of a charge being forced from one of the second cylinders into the cylinder in which the piston is driven by direct explosive force, valve controlled passages between the main and secondary cylinders, a valve casing, 10 pipes connecting end portions of the valve casing with the outer ends of the second set of cylinders, means for supplying motive medium to the valve casing, a valve arranged to operate in the said valve casing, 15 and means for operating the valve to direct the motive medium into one or the other of the said second set of cylinders.
2. In an internal combustion engine of the two-cycle type, the combination of oppositely disposed alining cylinders, pistons arranged to operate in said cylinders and connected for simultaneous movement in opposite directions, a second set of cylinders of larger diameter than the first mentioned cylinders and arranged in line therewith, guide sleeves of smaller diameter than the first mentioned cylinders and arranged concentric with the second set of cylinders and connected therewith at their outer ends, a second set of pistons connected with the first mentioned pistons and arranged to operate in the respective spaces formed between the second set of cylinders and the guide sleeves, valve controlled inlets at the inner ends of 30 the spaces formed between the second set of cylinders and the guide sleeves, and valve controlled passages between the inner ends of the first mentioned cylinders and the inner ends of the spaces formed between said second set of cylinders and guide sleeves, the valves controlling said passages being normally closed and adapted to be opened by direct action of the second set of pistons, the first mentioned cylinders having exhaust 35 openings which are controlled by the first mentioned pistons.
3. A two-cycle internal combustion engine comprising alining cylinders having valve controlled inlets at their inner ends and separated by a partition common to each, pistons arranged to operate in the cylinders and connected for simultaneous movement in opposite directions, concentric guide sleeves and cylinders connected at their outer ends 40 and arranged in line with the first mentioned cylinders and connected with the outer ends thereof, a second set of pistons connected with the first mentioned pistons to move therewith and arranged 45 to operate in the spaces formed between
- the concentric guide sleeves and cylinders, valve controlled inlets at the inner ends of the spaces formed between said concentric guide sleeves and cylinders, valve controlled passages between the inner ends 50 of the spaces formed between the concentric guide sleeves and cylinders and the inner ends of the first mentioned cylinders, the valves of said passages being positively actuated by the pistons arranged to operate in the spaces formed between the concentric guide sleeves and cylinders, piston controlled exhaust ports at the outer ends of the first mentioned cylinders, inlets at the outer ends of the spaces formed between the concentric guide sleeves and cylinders, and a valve controlled mechanism for admitting motive medium into the last mentioned inlets.
4. In combination two engine cylinders 80 having a tandem arrangement, pistons arranged to operate in said cylinders, means connecting the pistons to cause them to move in unison, other pistons connected with and at the outer ends of said engine pistons, cylinders for said second pistons to operate in, a valve casing, passages between said valve casing and the outer ends of the cylinders in which said second pistons operate, and a valve arranged to operate in 85 said valve casing to admit air to either one of the cylinders in which said second pistons operate, an explosive engine comprising engine cylinders having a tandem arrangement and provided at their inner ends with 90 inlets and having exhaust openings near their outer ends, pistons arranged to operate in the engine cylinders and provided with tubular extensions, annular pistons at the outer ends of said tubular extensions, means 95 connecting said annular pistons to cause the four pistons to move in unison, a pair of concentric cylinders at the outer end of each engine cylinder and receiving the annular piston which is adapted to operate in the 100 cylindrical space formed between a pair of the cylinders, passages connecting the inner ends of the spaces of the pairs of cylinders with the inlets of the remote engine cylinders, valves for closing the inlets of the engine cylinders, and stems extended from the valves and adapted to be engaged by the 105 said annular pistons.
- In testimony whereof I affix my signature in presence of two witnesses.
